STEAM SUPERHEATING INSTALLATION

John Edwin Wood, deceased, late of Altrincham, England, by Barclays Bank Limited, executor, London, England, assignor to The Superheater Company, New York, N. Y., a corporation of Delaware

Application June 12, 1942, Serial No. 446,848
In Great Britain October 14, 1940

1 Claim. (Cl. 261—114)

This invention relates to steam superheating installations of the kind in which the superheating is carried out in stages, and the control of the final steam temperature is effected by desuperheating the steam, by injecting water thereinto, between stages.

The present invention may extend to superheaters having more than two stages or passes, and known as multi-pass superheaters, or may be applied to a two-stage superheating installation, i. e. an installation comprising a primary section and a secondary or final section.

Where the water supplied for desuperheating the steam between the superheating stages is injected into the steam as it enters the inlet header of the secondary or final superheater there is a liability of the water being unequally distributed amongst the elements of the said superheater. This is undesirable, for, as will be appreciated, should some elements receive a relatively large proportion of water, resulting in the temperature of the steam leaving these elements being considerably below the mean final steam temperature, other elements receiving less water must work at steam temperatures considerably above the said mean final temperature with the liability of excessive metal temperature arising in such elements.

It is an object of the present invention to provide in a superheating installation of the kind indicated an improved steam temperature control apparatus of the intermediate water injection type from which the disadvantages arising from unequal water distribution amongst the elements of the respective section of the superheater concerned shall be absent, the invention seeking to provide a controlled superheater in which the injected water will be evaporated and distributed in the steam before the latter enters the elements of the secondary or other section of the superheater which immediately follows the water injection, without the provision of any external mixing device, such as an additional drum or vessel or a relatively long length of steam pipe, between the outlet and inlet headers of the primary and secondary superheaters respectively, or the equivalent headers of two sections of a multi-pass superheater.

Steam temperature control apparatus has been proposed in which the water required for desuperheating purposes between superheating stages is sprayed into the steam in the outlet header of a section of the superheater before the final section; according to the present invention all the water injected for desuperheat-

ing purposes into the steam in an outlet header of a section of the superheater preceding the final section is delivered thereinto at the end of such header remote from its outlet end, whereby before entering the elements of the final section of the superheater all said water is caused to traverse in the superheater, with the steam, a relatively long distance constituted by the length of such header, and to meet in the latter the streams of steam which issue thereinto from the elements connected thereto, and which set up in such header a state of turbulence effective to thoroughly mix the steam and water and ensure vaporisation of the latter.

In carrying the invention into practice, the water, in the case of a two-stage superheater, is injected into the outlet header of the primary section of the superheater. Where a multi-stage superheater is concerned, all the water required may be injected into the outlet header of either the primary or an intermediate section of the superheater, or a proportion of the water may be sprayed into the outlet header of one of said sections and the remainder into the corresponding header or headers of the other or others of said sections. Assuming a construction in which water for steam temperature control purposes may be delivered into two or more headers of the superheater, the apparatus may be such that a proportion of the water will be delivered in regulated quantity into each header whenever the control is operating, or it may be such that to effect a relatively small reduction in steam temperature a regulated quantity of water may be injected into one only of said headers and when a greater desuperheating effect is required, an appropriate amount of water may be delivered also into the other, or another of said headers.

It will be appreciated that where water is sprayed into the outlet header of any section of a multi-pass superheater preceding the penultimate section, at the end of such header remote from its outlet end, said water, in addition to being thoroughly mixed with the steam in said header, will traverse said penultimate section, and it may be another intermediate section or sections of the superheater, in which only a moderate temperature is reached, and will be fully vaporised before it can enter the elements of the final section.

An embodiment of the invention is illustrated diagrammatically in the accompanying drawing in which 1 and 2 are the inlet and outlet headers of the primary section of a two-stage super-

heater, and 3 and 4 the inlet and outlet headers of the secondary or final section of such superheater, 5 and 6 indicating the elements of the respective sections. Saturated steam enters the superheater by the pipe 7, and after passing through the primary section flows from one end of the outlet header 2 by way of the pipe 8 into the final section, leaving the latter for the superheated steam main or point of use by the pipe 9.

In the end of the header 2 remote from its connection with the pipe 8, i. e. remote from its outlet end, a water injecting device 10 is arranged, such device being fed with water by a pipe 11 equipped with a thermostatic valve 12, the temperature responsive element 13 controlling such valve being arranged in the path of the steam leaving the outlet header 4 of the final section of the superheater—conveniently as shown in the pipe 9 close to the said heater.

The water injecting device 10 may be a spray nozzle or nozzles of any known or appropriate type adapted to cause the water to issue in the form of a fine spray or mist, or it may be of the rose type adapted to deliver a large number of fine streams. As a further alternative, the water supply pipe 11 may project a short distance into the header 2 and be finely perforated at a relatively large number of points, the end of the pipe being closed except for any perforations it may be desired to provide in the end closure.

The manner in which the quantity of water injected into the steam will be regulated by the thermostatic control gear in order to maintain the final steam temperature constant, or approximately constant, at the predetermined degree, will be understood without further description herein.

It will be appreciated that the streams of steam issuing from the elements 5 into the header 2 set up considerable turbulence in such header, and that in consequence the water injected into the header by the device 10 will be thoroughly mixed with the steam as such water traverses the length of the header, and will be vaporised. Thus, by means of this invention unequal distribution of water amongst the elements of the final superheater of a controlled superheating installation of the type indicated, with its attendant disadvantages, is avoided in a simple, cheap and efficient manner without the employment of any external and relatively expensive mixing conduit or vessel.

15 What is claimed is:

In a superheater having elongated inlet and outlet headers with superheater tubes connected in parallel into openings in the side wall of said outlet header at a plurality of points spaced longitudinally thereof; an offtake pipe for superheated steam connecting with said outlet header at or closely adjacent one end thereof; and means for injecting water into said outlet header from the end thereof remote from said offtake pipe, said injecting means being positioned to introduce water in a direction axially of said header so all said water is caused to traverse with the steam a relatively long distance constituted by the length of said header and to be met in the latter by streams of steam issuing from the elements connected thereto.
